UNITED STATES PATENT OFFICE

2,388,589

INTERCEPTING APPARATUS

George V. Woodling, Rocky River, Ohio

Application July 27, 1942, Serial No. 452,403

7 Claims. (Cl. 114—240)

My invention relates in general to an intercepting apparatus and more particularly to an intercepting apparatus which may be employed to intercept a torpedo in a body of water which is directed to a vessel.

An object of my invention is the provision of an intercepting apparatus which may be employed in cooperation with a boat or vessel to intercept a torpedo which is directed toward the vessel or boat.

Another object of my invention is the provision of a maneuverable net which may be operated from a boat or vessel to intercept a torpedo which is directed towards the vessel or the boat.

Another object of my invention is the provision of utilizing submersible propeller-driven motors for moving a net through the water to intercept a torpedo directed toward a vessel or boat.

Another object of my invention is the arrangement of a plurality of submersible propeller-driven motors so that the motors may be individually controlled to give any directional movement to the motors through the water.

Another object of my invention is the provision of controlling a submersible propeller-driven motor at a place distant from the motor.

While I have described my invention as having utility in connection with intercepting torpedoes, it is to be understood that my invention may be used for other purposes wherein a submersible propeller-driven motor may be controlled at a place distant from the motor.

Other objects and a fuller understanding of my invention may be had by referring to the following description and claims, taken in conjunction with the accompanying drawing; in which:

Figure 1 shows a plan view of a boat or vessel having associated therewith my intercepting apparatus for intercepting a torpedo which is directed toward the boat or vessel;

Figure 2 is a modification of the arrangement shown in Figure 1 in that the intercepting apparatus may comprise a series of units as shown in Figure 1 to shield the entire side of the boat or vessel;

Figure 3 is a plan view of a net and two submersible propeller-driven motor units for moving the net through the water to intercept the torpedo or other object; and

Figure 4 is a side-elevational view of Figure 3 showing the intercepting apparatus in relationship to the water line of the body of water.

With reference to Figure 1, the reference character 10 indicates generally the plan view of a boat towards which a torpedo 13 is directed. The

torpedo is arranged to be intercepted by intercepting apparatus which comprises generally a net 14 which is moved through the water by two submersible propeller-driven motor units indicated generally by the reference character 12. As illustrated, each of the propeller driven motor units 12 is connected to a control equipment 15 on the boat through means of communicating lines or cables 16. Through the employment of suitable control equipment as indicated generally by the reference character 15, the operator on the boat 10 may govern the movement of the submersible propeller-driven motor units in any direction or speed to cause the net 14 to intercept a torpedo or other object directed toward the boat or vessel.

In the design of the submersible propeller-driven motor units 12, I preferably employ three submersible motors 17, 18 and 19 which are connected or arranged in a side-by-side and triangular relationship with each other. The two motors 17 and 18 are arranged to be buoyed up by means of a buoyant chamber 20 which provides a streamlined shell for the submersible motors 17 and 18. The buoyant chamber 20 may be reinforced to secure the two motors 17 and 18 in spaced relationship with each other so that the maneuverability of each of the propeller-driven motor units in a plane with the level of the water may be compared to that of a caterpillar tractor. That is to say, one of the submersible motors, for example 17, may be driven in a forward direction while the other motor 18, for example, may be driven in a rearward direction which forcibly turns the entire unit in a plane with the top of the water. The third submersible motor 19 is suspended below the buoyant chamber 20 by means of a tubular tie bar 21 so that as the two submersible motors 17 and 18 turn in a plane with the water, the tie bar 21 likewise turns the motor 19 in a corresponding direction. In the event that it becomes desirable to cause the submersible propeller-driven motor units 12 to submerge below the level line of the water, then the two submersible motors 17 and 18 are driven in a forward direction while at the same time the submersible motor 19 is arrested or driven in a reverse direction which causes the entire unit to dip down under the water. Consequently, by variably regulating the speed of the three submersible motors the entire propeller-driven motor unit may be caused to go in any three dimensional directions to give complete maneuverability thereto.

The submersible motors may be of any suitable

type, either the type which employs a water-tight housing through which the propeller shaft is sealed by a suitable seal or the type in which the stator windings are completely made water-tight by a castable resin or any other material which is unaffected by salt water. In a castable resin type of fluid type winding, the entire stator winding is embedded in the castable resin so that it is just as safe to operate the submersible motors in the water as it is in the air. The motors may be provided with relatively small rotors whereby the resistance to the rotation in the water is made relatively small as compared to the horsepower of the unit. The submersible motors may be several feet in length and may be characterized as "log" motors wherein a relatively high horsepower can be readily developed. In other words, the submersible motors may be of the type now employed for operating pumps below the water level in ships or in deep wells or other places. In Figure 1 the six small dots or circles represent the control to each one of the submersible motors. The current for controlling the energization of the motors is arranged to pass through the communicating lines or cables 16 to a stand pipe 24 which is connected to the buoyant chamber 20 that ties the two submersible motors 17 and 18 together. As illustrated in Figure 4, the top of the stand pipe 24 may be provided with a swivel 25 in order that the turning of the submersible propeller-driven motor units may not damage the cable 16 at the point it enters the top of the stand pipe 24. The electric cable for energizing the submersible motor 19 is carried down through the inside of the hollow tube or tie bar 21. In addition to controlling the motor units by electrical currents, the buoyant chamber 20 may be likewise controlled through suitable fluid pressure conduits or lines to aid in the regulation of the submersing of the motor units. That is to say, the depth to which the net and the motor unit may be submersed below the water line as indicated by the reference character 26 in Figure 4, may be controlled by a buoyant action by regulating the buoyant chamber 20 as well as by causing the motor unit to dip down under the water by varying the speed of the submersible motors 17 and 18 with respect to the submersible motor 19.

As illustrated in Figure 4, each end of the net 14 is anchored to the tubular tie bar 21 by means of a plurality of spaced collars 23 which engage the end wires of the net and which encompass the tubular tie bar 21. The top collar is supported by a shoulder 22 suitably fastened to the tubular tie bar 21. The shoulder 22 keeps the net from sliding down upon the tubular tie bar 21. The arrangement of the tubular tie bar 21 and the collar 23 enables the submersible propeller-driven motor units to turn in the plane of the water. Accordingly, in the maneuvering of the net 14 to intercept a torpedo, the net may be driven substantially parallel to the boat 10 until it gets into the path of the approaching torpedo, after which the motor unit may be operated or turned as shown in Figure 1 to go out to meet the torpedo coming in. The arrangement of the net and the size of the motor unit may be so proportioned that upon the torpedo striking the net, the torpedo will explode at a suitable safe distance from the boat. Alternatively, the net and the propeller-driven motor unit may be arranged to merely intercept the torpedo and change its direction of travel to miss the boat to which it was formerly directed. Upon the torpedo striking the net 14 the impact will probably be terrific enough to cause the motor

unit to wrap the net 14 about the torpedo so as to destroy its driving force. It is also conceivable that when the net 14 is wrapped around the torpedo, the motor units may be permitted to sink by destroying the buoyancy of the buoyant chamber 20 so that the torpedo and the motor units may be permitted to sink to a considerable depth by lengthening the communicating lines or cable 16 until the torpedo has expended its energy of motivation. The propellers of the motor units 12 may be enclosed in a suitable shroud so that these propellers do not become entangled in the net upon the torpedo striking the net.

The unit in Figure 4 is flexible and readily maneuverable and may be operated at a relatively high speed equal to that of a torpedo by making the horsepower of the "log" motors large. In some applications, it may be desirable to multiply the units as shown in Figure 4 to make a string of units as shown in Figure 2 which may be of sufficient length to shield the entire side of a boat as it moves through the water. The several units as shown in Figure 2 may be controlled and driven through the electric cables or lines from a suitable control as shown in Figure 1. Besides using the propeller-driven motor units for operating nets, they may be used as a tug or for any other purpose requiring the moving of an object through the water.

The cables or lines 16 in addition to supplying energy to the submersible propeller-driven motor units 12, act to steady the movement of the net 14. In other words, the cables may be kept taut so that a certain amount of control may be had over the movement of the submersible propeller-driven motor units. The cables may be wound about a reel or a plurality of individual reels so as to give individual control of the submersible propeller-driven motor units.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. A drive mechanism in a body of liquid comprising, in combination, a first submersible propeller-driven motor, a second submersible propeller-driven motor, means for connecting said motors together in substantially the same horizontal plane and in side-by-side relationship with respect to each other, means for buoying up said motors in said body of liquid, a third submersible propeller-driven motor suspended below said first and second motors and connected therewith, and means for individually operating said motors for directing the movement thereof, said operating means including a source of power externally of said buoying means and at a point remote therefrom and individual cables affixed to each of said motors and extending to the source of power.

2. A drive mechanism in a body of liquid comprising, in combination, a first submersible propeller-driven motor, a second submersible propeller-driven motor, means for connecting said motors together in substantially the same horizontal plane and in side-by-side relationship with respect to each other, means for buoying up said motors in said body of liquid, a third submersible propeller-driven motor suspended below said first and second motors and connected therewith by a

longitudinal member, a net, and means for connecting said net to said longitudinal member, means for individually operating said motors for directing the movement thereof, said operating means including a source of power externally of said buoying means and at a point remote therefrom and individual cables affixed to each of said motors and extending to the source of power.

3. A drive mechanism in a body of liquid comprising, in combination, a first submersible propeller-driven motor, a second submersible propeller-driven motor, means for connecting said motors together in substantially the same horizontal plane and in side-by-side relationship with respect to each other, means for buoying up said motors in said body of liquid, a third submersible propeller-driven motor suspended below said first and second motors and connected therewith, means for individually operating said motors for directing the movement thereof, said operating means including a source of power externally of said buoying means and at a point remote therefrom and individual cables affixed to each of said motors and extending to the source of power, and a net connected to said motors to intercept an object in said body of liquid.

4. A drive mechanism in a body of liquid comprising, in combination, a plurality of submersible propeller driven motors, means for connecting at least two of said motors together in substantially the same horizontal plane and at a distance from and substantially parallel to each other, means for buoying up said connected motors in said body of liquid, tying means for connecting at least another motor at a distance below the said at least two connected motors, and means for individually operating said motors for directing the movement thereof, said operating means including a source of power externally of said buoying means and at a point remote therefrom and individual cables affixed to each of said motors and extending to the source of power.

5. A drive mechanism for moving an object in a body of liquid comprising, in combination, a plurality of submersible propeller driven motors, means for connecting at least two of said motors together in substantially the same horizontal plane and at a distance from and

substantially parallel to each other, means for buoying up said connected motors in said body of liquid, tying means for connecting at least another motor at a distance below the said at least two connected motors, and means for individually operating said motors for directing the movement thereof, said operating means including a source of power externally of said buoying means and at a point remote therefrom and individual cables affixed to each of said motors and extending to the source of power, said object being connected to said tying means.

6. A drive mechanism in a body of liquid comprising, in combination, a plurality of submersible propeller driven motors, means for connecting at least two of said motors together in substantially the same plane and at a distance from and substantially parallel to each other, means for buoying up said connected motors in said body of liquid, and means for individually operating said motors for directing the movement thereof, said operating means including a source of power externally of said buoying means and at a point remote therefrom and individual cables affixed to each of said motors and extending to the source of power, said submersible propeller driven motors each having a liquid-tight winding and being directly submersible in said liquid.

7. A drive mechanism in a body of liquid comprising, in combination, a plurality of submersible propeller driven motors, means for connecting at least two of said motors together in substantially the same plane and at a distance from and substantially parallel to each other, means for buoying up said connected motors in said body of liquid, and means for individually operating said motors for directing the movement thereof, said operating means including a source of power externally of said buoying means and at a point remote therefrom and individual cables affixed to each of said motors and extending to the source of power, said submersible propeller driven motors each having a liquid-tight winding and being directly submersible in said liquid, said motors each having a rotor directly rotatably mounted in said liquid.

GEORGE V. WOODLING.
